SHOE SOLE PROTECTING DEVICE

Charles S. Staresina, Cleveland, Ohio

Application July 4, 1939, Serial No. 282,807

10 Claims. (Cl. 36—72)

An object of my invention is to provide a device which will enable a person to apply shoe dressing to the surface of a shoe without smearing the dressing on the sole extension or on the sole edge.

5 Another object of my invention is to provide a device which will protect the sole and heel edges from shoe dressing.

Another object of my invention is to provide a single device for baby shoes which is reversible for 10 use on both the right and left shoes.

Another object of my invention is to provide a device for aiding in cleaning shoes in which an adjustment is embodied thereby increasing the utility of the device.

15 Still another object of my invention is to provide a device for protecting shoe sole extensions which is flexible to permit adjustment for various different shapes of shoes.

Still another object of my invention is to provide 20 a sole guard which temporarily attaches to the sole of a shoe thereby obviating the necessity of the person holding the device against his shoe.

A further object of my invention is to provide tabs on the device which engage the shoe sole to 25 retain the device in its proper position with respect to the shoe.

Another object of my invention is to provide simple means for attaching my device to a shoe.

Other objects and a fuller understanding of my 30 invention may be obtained by referring to the following description and claims, in which:

Figure 1 is an isometric view of one embodiment of my invention showing a device adapted for use on an adult's shoe.

35 Figure 2 is an isometric view of another embodiment of my invention showing a device adapted for use on a baby's shoe.

Figure 3 is a cross sectional view taken along line 3—3 of Figure 1 showing a portion of a shoe 40 and sole upon which is mounted the device.

Figure 4 is a cross sectional view taken along line 4—4 of Figure 1 and shows the telescopic arrangement which permits for size adjustment.

45 Figure 5 is a cross sectional view taken along line 5—5 of Figure 2 showing the clasp which is used to hold the two ends of the device together.

And Figure 6 is a cross sectional view taken along line 6—6 of Figure 1 and shows a portion of a baby's shoe and sole upon which is mounted the 50 device.

With reference to Figure 1 of the drawing my invention is a sole and heel protecting device for shoes and comprises a vertical wall 11 and an inwardly turned top surface 12. The protecting device 10 is adapted to prevent shoe dressing such

as "shoe milk" or other whitening preparations from soiling the sole and heel sides and from soiling the sole and heel extensions. The sole and heel extensions are the projections of the sole and heel beyond the uppers.

5 As illustrated in Figure 1 of the drawing my device may be made in three parts or, as illustrated in Figure 2, it may be made in a single piece. However, it is to be understood it is within the purview of this invention that any number of parts may be used to achieve the same results.

Figure 1 shows a preferred embodiment for an adult's shoe. It comprises a front portion 14, an outside heel portion 15 and an inside heel portion 16. Each of the portions 14, 15, and 16 have an inwardly turned top surface 12. It may be seen from the drawing that the inwardly turned top surface 12 of the portions 15 and 16 are not so wide as the inwardly turned top surface 12 of the front portion 14. This is for the reason that the 20 heel of a shoe does not extend beyond the upper so much as the sole does. The outside heel portion 15 is provided at one end with part of a clasp member 19 and the inside heel portion 16 is provided at one end with a complementary part of a clasp member 20. These two parts are adapted 25 to engage each other, as may be seen in Figure 5, and hold the heel portions of the device 10 together. I have provided telescopic means for longitudinally adjusting the device to enable one 30 device to be used with shoes of different lengths. This adjustment means is identified by numeral 21 in Figure 1 and is made by folding part of the vertical wall 11 of each heel portion 15 and 16 into a narrow U-shaped passageway 22 and positioning the vertical wall 11 of the front portion 14 into the U-shaped passageway 22. This telescopic 35 adjusting means is preferably placed near the instep of the shoe where there is a minimum amount of curvature to the outline of the sole and where the sole extension beyond the upper is of such an extent to allow a fairly wide inwardly turned top surface 12. The width of the top surface 12 and the U-shaped passageway 22 prevent the heel portions 15 and 16 from separating vertically from the front portion 14. To prevent the portions from separating longitudinally, I crimp 40 the heel portions 15 and 16 to form a depressed groove 23 and crimp each end of the forward portion 14 to form raised stop portions 24. The raised stop portions 24 are adapted to slide in the depressed groove 23 but as the depressed groove 23 does not extend to the end of the heel portions 15 and 16 the front and heel portions are prevented from separating longitudinally by the

raised stop portions 24 engaging the forward edge of the depressed groove 23.

At spaced intervals around the vertical wall 11 of the forward portion 14 I have provided lugs 25 which engage the bottom of the sole of the shoe which is being dressed thereby holding the shoe and the device in a fixed relationship with each other. When the lugs 25 engage the shoe sole properly and when the clasp members 19 and 20 are in engagement the device will remain positioned on the shoe in a proper place to protect the sole sides and the sole extensions without the aid of a person's hand.

Figure 3 is a cross sectional view taken along line 3-3 of Figure 1 and shows the device of Figure 1 in place on a shoe 29. Figure 3 shows the manner in which the lug 25 engages the sole 30 to hold the inwardly turned top surface 12 in place.

Figure 4 is a cross sectional view taken along the line 4-4 of Figure 1, showing the telescopic means 21 in detail. Numeral 16 indicates the heel portion which is folded at the bottom into a U-shaped passageway 22. In the passageway 22 the forward portion 14 is slidably mounted. The depressed groove 23 is illustrated and the raised stop portion 24 is shown slidably positioned in the depressed groove. As the depressed groove 23 tapers into the inside heel portion 16 it provides a retaining wall at each end which engages the raised stop portion 24 thereby preventing the heel portion 16 from separating from the forward portion 14 when the telescopic means is actuated.

Figure 5 is a cross sectional view taken along line 5-5 of Figure 1 and shows the two complementary clasp members 19 and 20 in engagement with each other.

In Figure 2 I have shown another preferred embodiment of my invention which finds particular utility in use with baby shoes. It comprises a vertical wall 11, an inwardly turned top surface 12 and an inwardly turned bottom surface 13. With the top surface 12 facing upward the left shoe of a pair of baby shoes may be positioned in the device and cleaned. The inwardly turned top surface 12 prevents the dressing from soiling the sole of the shoe. With the inwardly turned bottom surface facing upward the right shoe of the pair of baby's shoes may be treated in the same manner. Thus it will be seen that my embodiment shown in Figure 2 is reversible and only one device is necessary to serve both the right and the left shoes of a pair. I have provided my reversible device shown in Figure 2 with a pair of complementary clasp members 19 and 20. These members are similar to the clasp members 19 and 20 of Figure 1 and serve the same purpose. Further, I have provided my reversible device with lugs 25 similar in design and purpose to the lugs 25 in Figure 1. Figure 6 is a cross sectional view taken along line 5-5 of Figure 2 and shows the reversible device as positioned on a baby shoe 31.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A device for protecting the sole extension of shoes comprising, in combination, a length of flexible non-elastic material having an angularly disposed surface adapted to cover the said sole extension and having spaced tabs adapted to

engage the sole of the shoe thereby holding the angularly disposed surface against the sole extension.

2. A device for protecting the edges of shoe soles and the sole extension comprising, in combination, a length of flexible non-elastic material adapted to engage the sole edges, said length of material having an inwardly turned edge adapted to cover the said sole extension and having spaced tabs adapted to engage the sole of the shoe thereby holding the turned edge against the sole extension.

3. A device for protecting the edges and extensions of shoe soles comprising, in combination, a length of flexible non-elastic material adapted to conform to the shape of the shoe sole and heel thereby protecting their edges and having complementary clasp means at each end for engaging to hold said length of material to said shoe, said length of material having an inwardly turned edge adapted to cover the said sole extension and having spaced tabs adapted to engage the sole of the shoe thereby holding the turned edge against the sole extension.

4. A device for protecting the edges and extensions of shoe soles and heels comprising, in combination, a sole protector comprising a length of flexible non-elastic material adapted to conform to the shape of the shoe sole thereby protecting the sole edges, a heel protector comprising a length of flexible non-elastic material adapted to conform to the shape of the heel thereby protecting the heel edges, and telescopic means adapted to adjustably connect said sole protector to said heel protector.

5. A device for protecting the edges and extensions of shoe soles and heels comprising, in combination, a sole edge protector comprising a length of flexible non-elastic material adapted to conform to the shape of the shoe sole, a heel edge protector comprising an outside length of flexible non-elastic material adapted to conform to the shape of the outside edge of the heel and an inside length of flexible non-elastic material adapted to conform to the shape of the inside edge of the heel, telescopic means for adjustably connecting said outside heel protector and said inside heel protector to said sole protector and clasp means for securing said outside and inside heel protectors together, said lengths of material having inwardly turned edges for protecting the sole and heel extensions.

6. A device for protecting the edges and extensions of shoe soles and heels comprising, in combination, a length of flexible non-elastic material having complementary clasp means at each end thereof and adapted to conform to the shape of the sole and heel of a shoe, said length of material having inwardly turned top and bottom edges adapted to cover the sole and heel extensions, and spaced tabs located on said flexible non-elastic material substantially mid-way between said turned top and bottom edges to engage the sole of the shoe thereby holding the turned edge against the sole extension.

7. A device for protecting the edges and extensions of a pair of shoes comprising, in combination, a length of non-elastic material shaped to conform to the outline of a shoe and having inwardly turned top and bottom edges adapted to protect the shoe extensions of both the right and left shoes, said length of material having complementary clasp means on each of its ends adapted to engage each other to hold said device in place on a shoe.

8. A device for protecting the edges and exten-

5 sions of a pair of shoes comprising, in combination, a length of material adapted to conform to the outline of a shoe and having an inwardly turned top edge adapted to protect the extensions of one shoe of the said pair and having an inwardly turned bottom edge adapted to protect the extensions of the other shoe of the pair.

10 9. A device for protecting the edges and extensions of a pair of shoes comprising, in combination, a length of material adapted to conform to the outline of a shoe and having an inwardly turned top edge adapted to protect the extensions of one shoe of the said pair and having an inwardly turned bottom edge adapted to protect the extensions of the other shoe of the pair, said length of material having two ends, each end constituting complementary attaching means adapted to engage the other to fasten said device to a shoe.

15

10 10. A device for protecting the edges and extensions of a pair of shoes comprising, in combination, a length of material adapted to conform to the outline of a shoe and having an inwardly turned top edge adapted to protect the extensions of one shoe of the said pair and having an inwardly turned bottom edge adapted to protect the extensions of the other shoe of the pair, said length of material having two ends, each end constituting complementary attaching means adapted to engage the other to fasten said device to a shoe, and tab means located on said device substantially mid-way between said top and bottom turned edges to engage the sole of the shoe to maintain the device in its proper position. 15
